[57] CLAIM

The ornamental design for a child's pillow, substantially as shown and described.

DESCRIPTION

FIG. 1 is a front elevational view of a child's pillow
showing my new design;

FIG. 2 is a right side elevational view of FIG. 1, the left side elevational view being a mirror image thereof;

FIG. 3 is a top plan view of FIG. 1;

FIG. 4 is a bottom plan view of FIG. 1; and,

FIG. 5 is a rear elevational view of FIG. 1.

In FIGS. 3-5 the vertical lining on the pouch is intended to show that most of the pouch is red.
